CLAIM

The ornamental design for the front face of a vehicle wheel, as shown and described.

DESCRIPTION

FIG. 1 is a perspective view of the front face of a vehicle wheel according to the present invention; and,

FIG. 2 is a front elevational view of the front face of a vehicle wheel as shown in FIG. 1.

The broken line showing of the tire and within the central hub area of the wheel is for illustrative purposes only and forms no part of the claimed design.
